(57) **CLAIM**

The ornamental design for a combination golf ball tool and stroke indicator, as shown and described.

DESCRIPTION

FIG. 1 is a top plan view of a combination golf ball tool and stroke indicator device showing my design;

FIG. 2 is a bottom plan view thereof;

FIG. 3 is a left side elevational view thereof, the right side

elevational view thereof being a mirror image of FIG. 3;

FIG. 4 is a front elevational view of the FIG. 1 device;

FIG. 5 is a rear elevational view of the FIG. 1 device;

FIG. 6 is a perspective view taken from above and to a side of the device as shown in FIG. 1; and,

FIG. 7 is a perspective view taken from in back and to a side of the FIG. 1 device.

The broken line showing of stroke (FIGS. 1 and 6) is for illustrative purposes only and forms no part of the claimed design.
